By Geo. A. Hutchinson
Attorney.

UNITED STATES PATENT OFFICE.

WILLIAM REDFORD MULOCK, OF WINNIPEG, MANITOBA, CANADA.

SLED-PROPELLER.

1,401,275.

Specification of Letters Patent. Patented Dec. 27, 1921.

Application filed March 26, 1921. Serial No. 455,913.

To all whom it may concern:

Be it known that I, WILLIAM REDFORD MULOCK, a subject of the King of Great Britain, and resident of Winnipeg, in the 5 Province of Manitoba, Dominion of Canada, have invented certain new and useful Improvements in Sled-Propellers, of which the following is a full, clear, and exact specification.

10 This invention relates to means for manually propelling sleds or other vehicles and has for its object to provide simplified poling apparatus for this purpose.

The invention contemplates the use of 15 propelling poles or rods shod with metal and flexibly connected to opposite sides of the sled so that they may be freely moved for poling the sled along. A special object of the present invention is to provide improved means 20 for attaching the flexible connections at one end to the sled and at the other end to the poles, the latter connection preferably allowing for additional play or movement of said pole with respect to the sled.

25 The invention will be first hereinafter described in connection with the accompanying drawings, which constitute part of this specification, and then more specifically defined in the claims at the end of the description.

30 In the accompanying drawings, wherein similar reference characters are used to designate corresponding parts throughout the several views:

35 Figure 1 is a perspective view of a sled with propelling poles attached thereto in accordance with the preferred form of this invention.

40 Fig. 2 is a detailed elevation, drawn to a larger scale, of one of the connector disks used for attaching the chains to the sled.

45 Fig. 3 is a central vertical section of said connector disk attached to one side of the sled and showing the connection of the chain therewith, and

Fig. 4 is a side view of a sled showing a modified form of connection between the chain and pole.

50 Referring first to Figs. 1, 2 and 3 of the drawings, 1 designates a sled to each side of which a propelling pole 2 is attached by means of a chain 3. At one end of each chain there is a ball or head 4 attached thereto by a reduced shank 5, while at the other

end of said chain a ring 6 is suitably fastened. The ball 4 is engaged with a connector disk 7 fastened to the side of the sled by screws 70 and having a vertical pocket or passage 8 leading from its upper edge to the central portion thereof into which said ball 60 is dropped. A restricted slot 9 in the front face of the disk 7 communicates with and extends along the passage 8 and at the lower end leads into a somewhat larger opening 10 extending from the outer face of said disk to 65 communicate with the lower end of the passage 8. When the ball 4 is dropped into said passage or pocket 8, its shank 5 passes through the slot 9 until it reaches the opening 10 which is smaller than said ball and 70 consequently retains the latter in engagement with the disk 11 while allowing universal movement of the shank 5 in said opening 10.

The ring 6 on the free end of each of the 75 chains 3 is loosely mounted around the corresponding pole 2 to have free sliding movement thereon between fixed collars or abutments 11 on said pole. Said collars may be located and spaced on the pole as desired to 80 permit more play or movement of the latter with respect to the sled than is permitted by the length of chain 3 illustrated. By this means, the same degree of play may be obtained with a shorter chain as would be possible with a much longer chain if the latter were fixedly attached to the pole.

In use, a child seated on the sled and facing the front end thereof grasps the forward ends of the poles 2 and reciprocates 90 said poles in the same manner as in poling a boat. The rear ends of the poles are shod with metal tips 12 of any suitable shape to engage the surface of snow or ice over which the sled passes.

As shown in Fig. 4, a pole 20 is attached to the side of a sled 21 by means of a chain 22, one end of which is fastened to said sled by a disk 23 similar to the disk 7 already described, while the other end of said chain is attached to a collar 24 fixedly fastened to said pole. If the chain 22 is the same length as the one shown at 3 in Fig. 1, the play of the pole 20 will be more restricted than that of the pole 2, owing to the fixed connection 100 between said chain 22 and pole 20. However, the chain 22 may be made long enough, if desired, to allow for substantially the

same play of the pole 20 as is permitted by the shorter chain 3 and sliding ring 6 to the pole 2.

I claim:

- 5 1. The combination with a vehicle, of poles for propelling the same, and linear connections of flexible non-elastic material, each secured at one end to the vehicle and at the other end to an intermediate point on one
- 10 10 of the poles whereby said poles have free longitudinal and rotary movement with respect to the points of attachment of the linear connections to the vehicle.
- 15 2. The combination with a vehicle, of poles, flexible connections between said poles and the vehicle, the ends of said flexible connections which are attached to the poles being adapted to slide thereon, and means for limiting said sliding movement of the flexible
- 20 20 connections on the poles.
- 25 3. The combination with a vehicle, of poles having spaced abutments thereon, flexible connections attached at one end to the vehicle, and rings on the other ends of said flexible connections mounted to slide on the poles between said abutments.

4. The combination with a vehicle, of poles, flexible connections between said poles and vehicle, headed shanks on the ends of said flexible connections and connector disks 30 secured to the vehicle and to which said flexible connections are attached by said headed shanks.

5. The combination with a vehicle, of poles, flexible connections between said poles 35 and the vehicle, connector disks secured to the vehicle and having pockets extending radially from their upper edges, restricted slots in the front faces of said disks communicating with and extending along said pockets, 40 there being enlarged openings at the lower ends of said slots also communicating with said pockets, and headed shanks on the ends of said flexible connections, the heads on said shanks engaging said pockets in said 45 disks and said shanks extending through said enlarged openings and having universal movement therein.

In testimony whereof I have signed my name to this specification.

WILLIAM REDFORD MULOCK.
